UNITED STATES PATENT OFFICE.

LEWIS L. ROMANS, OF MEMPHIS, TENNESSEE.

HANDSAW-LUBRICATOR.

1,178,413.

Specification of Letters Patent.

Patented Apr. 4, 1916.

Application filed May 4, 1915. Serial No. 25,725.

To all whom it may concern:

Be it known that I, LEWIS L. ROMANS, a citizen of the United States, residing at Memphis, in the county of Shelby and State of Tennessee, have invented new and useful Improvements in Handsaw-Lubricators, of which the following is a specification.

This invention relates to hand saw lubricators and one of the principal objects of the invention is to provide a simple and efficient device which can be carried by the handle of the saw and by which a predetermined amount of oil may be fed to the blade when desired.

Another object of the invention is the provision of a device of this character having a plunger actuated valve which may be locked against movement or in which the plunger can be rendered inoperative to actuate the valve.

Another object of the invention is the provision of a device of this character which may be conveniently adapted or removed from a handle of an ordinary hand saw which may be filled without removing the device from the handle and which when removed to have its parts so arranged that oil cannot escape therefrom.

Further objects of the invention will appear as the following specific description is read in connection with the accompanying drawings which form a part of this application and in which:

Figure 1 is a side elevation of a saw handle showing the device applied thereto, Fig. 2 is a transverse section taken on the line 2—2 of Fig. 1, Fig. 3 is a longitudinal section, Fig. 4 is a detail top plan view, Fig. 5 is a bottom plan view of the top cap removed from the casing, Fig. 6 is a sectional view of the casing.

Referring more particularly to the drawings 1 represents the handle of the saw provided as is usual with the blade kerf 2 in which the blade 3 is seated. The forward wall of the finger opening is cut away as shown in Figs. 2 to 4 and the connecting upper member between the cap and the blade holding portion of the handle is vertically apertured as shown at 5. Mounted within the recess 4 is a casing 6 having a threaded extension projecting from its lower end upon which is threaded a closing and adjusting cap 7 having a discharge nipple 8 depending therefrom. The cap 7 rests upon a seat 9 formed in the handle and the nipple

8 registers with a port 10 extending from the seat to the lower part of the handle and communicating with the upper end of the casing.

Removably threaded upon the upper end of the cylinder is a cap 11 having a longitudinally extending tube 12 closed at its lower end by a ported disk 13 and at its upper end by a spider 14. Slidably mounted within the tube 12 is a valve plunger 15 carrying upon its lower end a crescent-shaped valve a disk 16 which closes the port in the disk 13. This plunger is normally elevated by a spiral spring 17 which extends between the disk 13 and a collar 18. The outer end of the plunger is provided with an operating button 19 having an eccentric aperture 20 through which oil may be fed to the tube and thereby to the casing 6, the cap 11 being vented as shown at 21 to permit the escape of air after the casing is filled with oil. Covering one-half of the upper end of the cylinder is a semi-circular plate 22 in which the end 23 of a valve plunger 24 is slidably mounted. This plunger carries upon its lower end a valve 25 arranged to close the port 26 in the extension of the casing and being normally held in closed position by a spiral spring 27 which surrounds the plunger 24 between the lower wall of the extension and the off-set 28 on the plunger. The cap 7 is so constructed that when fully screwed upon the extension that the lower wall of the base thereof will engage the valve 25 and prevent the depression of the plunger. While the valve disk 16 is made crescent-shaped so that when in one position it will engage the eccentric end of the plunger while in another position the plunger 15 may be depressed without effecting an operation of the plunger 24.

In placing the device within the saw handle the cap 11 is first placed in position with the tube passing through the ball 5. The casing with the cap 7 fully screwed thereon is then placed in position and screwed into the cap 11. The cap 7 is then unscrewed until it rises against the seat 9. Further unscrewing of the cap 7 causes the cap 11 to bear against the upper portion of the handle and thus the entire device is clamped into position and the valve 25 made free to uncover the port 26 when desired. In this position the plunger 15 may be depressed against the tension of the spring 17 which will cause the valve disk 16 to engage the

eccentric end of the plunger 24 thereby operating said plunger against the tension of the spring 27 and removing the valve 25 from the port 26. As long as the plunger 15 is held down in this manner oil will continue to flow through the port 26 and nipple 28 to the valve. Immediately upon release of the plunger the springs 27 and 17 will restore the parts to normal position. 10 By turning the plunger 15 the cut-away portion of the crescent shaped disk 16 will permit the plunger 15 to be fully depressed without actuating the plunger 24. By depressing the plunger 15 and inserting the 15 spout of an oil can in the opening 20 the casing 6 may be filled with oil without removing the device from the saw handle.

What is claimed is:—

1. In a lubricating device for hand saws, 20 a casing having a discharge port, means for holding the casing within the handle of the hand saw, a valve for controlling the discharge from the port, a spring retracted plunger connected to the valve and having 25 an off-set end, a spring retracted plunger operating member having a crescent-shaped end to engage the offset end of the plunger and an apertured operating button for the plunger operating member, said crescent-shaped end acting as a valve. 30

2. In combination with a saw handle, said handle being provided with a seat and with a support opposite to said seat, a tubular member projecting into said support, an enlarged cap integrally formed upon said tubular member, a casing threaded into said cap and having a closed bottom, an adjusting cap secured into said seat and threaded upon the closed bottom portion of said casing, to hold said member against said support, a spring pressed valve arranged in said casing, the closed bottom of said casing having a port and said seat having a passage for communication with said port, said valve controlling said port, and means in said tubular member for controlling said valve. 45

3. In combination, a saw handle, a lubricant containing casing carried by said handle, means for supporting said casing upon 50 said handle, said casing having a feed port, a semi-circular plate mounted at the upper end of said casing, a valve rod passing into said casing and its port, an eccentric portion formed upon said valve rod and projecting into said plate, a manually controlled reciprocating member carried by said handle, a crescent-shaped horizontally disposed member carried by said reciprocating member, said crescent-shaped member being dis-

posed in said casing and movable to position 60 to engage said eccentric portion, a coil spring surrounding said valve rod against which said rod is depressed and a valve carried by said valve rod adapted to close said port. 65

4. In combination, a saw handle, said handle provided with a hand receiving recess, a seat formed upon said recess portion and having a discharge port, a second seat formed upon said portion opposite said first named seat, a casing having at each end a reduced threaded nipple, a longitudinally extending tube projecting into said second seat and having an integral cap formed with perforations and engaging one 75 of the threaded nipples of said casing, an adjusting cap having a discharge nipple received in said first named seat and communicating with the ports thereof, said adjusting cap engaging the opposite threaded nipple 80 of said casing whereby to support the same, a spring supported valve rod in said longitudinally extending tube adapted to be depressed, a swivelable member carried by said rod adapted to close said perforations, 85 and means engageable by said valve for conveying oil from said casing through said discharge nipple and said port.

5. In a device of the class described, in combination a support, an oil containing 90 casing mounted therein, said casing having a discharge port, a valve adapted to close said port, a valve rod connected to said valve and extending upwardly into said casing, a spring coiled about said valve rod, in said 95 casing, a depressing pin carried by said valve rod and engaging said spring, a crank formed as an offset upon said valve rod, a circular plate in said casing through which said crank projects, a housing upon said 100 casing, a plunger rod in said housing, a spring against which said plunger rod is depressed, a button carried by said plunger rod, said housing having a port communicating with said casing, and a valve controlled by said plunger rod normally closing 105 said last named port, said last named valve being crescent-shaped and having an edge adapted to swivel about in said casing to clear said crank, said crescent-shaped 110 valve being operable to depress said crank whereby to unseat said first named valve.

In testimony whereof I affix my signature in presence of two witnesses.

LEWIS L. ROMANS.
